United States Patent Office

Des. 197,058
Patented Dec. 10, 1963

197,058

CHAIR

Ronald Beckman, New York, N.Y., and William J. Cannan, Rutherford, N.J., assignors to Herman Miller, Inc., Zeeland, Mich., a corporation of Michigan

Filed Nov. 13, 1962, Ser. No. 72,462

Term of patent 14 years

(Cl. D15—1)

FIG. 1.

FIG. 2.

FIG. 3.

FIG. 4.

FIG. 5.

FIG. 6.

FIG. 1 is a front perspective view of a chair showing our design wherein the body portion is formed of six segmental cushion members;

FIG. 2 is a back elevation of the chair shown in FIG. 1;

FIG. 3 is a side elevation of the chair shown in FIG. 1;

FIG. 4 is a front perspective view of the chair of FIG. 1 wherein the body portion is formed of five segmental cushion members;

FIG. 5 is a back elevation of the embodiment shown in FIG. 4; and

FIG. 6 is a side elevation of the embodiment shown in FIG. 4.

The sides not shown in FIGS. 3 and 6 are the same in appearance as the sides shown.

We claim:

The ornamental design for a chair, substantially as shown and described.
